CLAIM

We claim the ornamental design for a vacuum cleaner
nozzle, as shown and described.

DESCRIPTION

FIG. 1 is a front view of a vacuum cleaner nozzle showing
the claimed design;

FIG. 2 is a rear view of FIG. 1;

FIG. 3 is a bottom view of FIG. 1;

FIG. 4 is a right view of FIG. 1;

FIG. 5 is a left view of FIG. 1;

FIG. 6 is a perspective front, bottom, left view of FIG. 1; and
FIG. 7 is a perspective rear, bottom, right view of FIG. 1.

FIG. 8 is a front view of the vacuum cleaner nozzle
according to a second embodiment;

FIG. 9 is a rear view of FIG. 8;

FIG. 10 is a bottom view of FIG. 8;

FIG. 11 is a right view of FIG. 8;

FIG. 12 is a left view of FIG. 8;

FIG. 13 is a perspective front, bottom, left view of FIG. 8;
and,

FIG. 14 is a perspective rear, bottom, right view of FIG. 8.
The broken lines in the drawings depict portions of the
vacuum cleaner nozzle that form no part of the claimed
design.

1 Claim, 8 Drawing Sheets
